UNITED STATES PATENT OFFICE.

NEWTON R. WILSON, OF SOCORRO, TERRITORY OF NEW MEXICO.

CRUCIBLE FOR LEAD-FURNACES.

SPECIFICATION forming part of Letters Patent No. 416,085, dated November 26, 1889.

Application filed January 19, 1888. Serial No. 261,815. (No model.)

To all whom it may concern:

Be it known that I, NEWTON R. WILSON, a citizen of the United States, residing at Socorro, county of Socorro, and Territory of New Mexico, have invented certain new and useful Improvements in Crucibles for Lead-Furnaces, of which the following is a specification.

The invention relates to a detached crucible to be used in lead-smelting for the separation of lead or bullion from matte, speiss, and slag, and has for its object the overcoming of the difficulties which are common in crucible furnaces—frequent solidification of the molten matter in the bottom of the furnace.

The invention will be first fully described with reference to the accompanying drawings, and then be specifically pointed out in the claims.

In said drawings, Figure 1 is a plan view of the body of my improved crucible. Fig. 2 is a vertical axial section thereof in position for discharging into the bullion-molds. Fig. 3 is an end view showing the crucible in position for tilting. Fig. 4 is a perspective view showing the protecting-screen and the removable partition, the latter raised.

The crucible consists of a cast-iron box or bowl 1, preferably made with its sides tapering toward the bottom and in sections bolted together or in one piece, as desired. It is divided unequally into two compartments by a movable partition 2, which is complementary in shape to the cross-section of the bowl and rests against the flanges 3, and has lugs 4 sliding over said flanges and holding it thereto. The large compartment I designate the "slag-compartment" and the small one the "lead-compartment." The partition projects slightly above the top of the bowl and has a hole in it near the top for the insertion of a bar employed to raise and lower the partition. When raised, the partition may also be supported by passing a chain 2^a through this hole.

The bowl 1 has a non-conducting jacket, consisting of a sheet-iron casing 5, fixed to the bowl by bolts 6, and containing any suitable non-conducting material 7, such as mineral wool. If desired, a cover similarly made to this jacket may be employed for the slag-com-

partment part of the bowl to retain the heat still more effectually. The spout 8 at the top of the large compartment is for the overflow 55 of slag. Similar spout 9, a little lower down, is for the discharge of matte and speiss, while the spout 10, having opening 11 formed in a cast-iron projection from the bottom of the lead-compartment side of the bowl, is for the 60 discharge of lead.

12 are a number of bullion-molds set upon a truck, which may consist of track-wheels 13, cross-bars 14, tie-bars 15, and sills 16. The latter may be made of ordinary railroad- 65 iron, as shown in Fig. 3. Cast upon each end of the bowl 1 are arms 17, bored to receive trunnions 18, shrunk therein. Upon these trunnions the bowl tilts, resting on a frame 19, carried by a truck 20. On the base of the 70 bowl is secured a ring 21, to which may be connected a hook 22 on chain 23, which is brought into operation by block and tackle 24, suspended from a suitable derrick 25.

Hanging over the crucible and extending 75 down upon the side away from the furnace between the lead and slag compartments is a screen 26, made by riveting two pieces of sheet-iron to a light iron frame, leaving air-space between. The movable partition be- 80 ing luted with clay and lowered into position, and the hole at the bottom of the lead-compartment and the tap-hole for matte 9 being stopped with plugs of clay, the crucible is run up in front of the smelting-fur- 85 nace so that the spout from the furnace projects over into the slag-compartment at the point C. The furnace is now tapped and the lead or base bullion, matte, speiss, and slag are all allowed to flow into the slag-compart- 90 ment of the crucible.

The different substances arrange them- 95 selves in the crucible according to their spe- cific gravities, the lead being on the bottom and the slag on top. When the slag-com- partment is full, the slag overflows through the spout 8 and is caught in slag-pots and removed. When lead has accumulated in the slag-compartment to the depth of about one foot or more, a bar is inserted through 100 the hand-hole in the top of the movable par- tition 2 and the partition raised a few inches and held in position by the chain 2^a, Fig. 4. Lead immediately flows into the lead-com-

partment, the partition not being raised sufficiently to allow any matte, speiss, or slag to flow into the lead-compartment.

As the lead accumulates in the crucible it 5 may be dipped from the lead-compartment or tapped through the hole 11 into the molds on the movable rack below. At intervals matte and speiss are tapped through the hole 9, or the partition is raised sufficiently to allow 10 them to flow into the lead-compartment, where they quickly solidify on the top of the lead and may be removed in cakes.

The screen 26, Fig. 4, is hung in position 15 to protect the workmen from the heat and smoke when dipping or tapping lead.

The constant flow of molten material into the crucible and the fact that it is surrounded by a non-conducting substance keeps its contents fluid for a long time. Gradually, 20 however, it solidifies around the sides and top, and it becomes necessary to remove it from the furnace and substitute another. All the lead in the crucible is now allowed to flow through the hole 11 into the bullion-molds. 25 The crucible is then pushed away from the furnace and run under a derrick, Fig. 3, on which is hung a pulley. The movable partition is now lifted out of the crucible, leaving a small space between the chilled contents and the 30 flange 3. A chain is now attached to the ring at the bottom of the crucible and to the pulley, Fig. 3, when the bowl of the crucible

is inverted and its contents allowed to drop into a pit below.

An apparatus similar to this is also shown 35 and described in my applications, Serial No. 282,722, filed August 4, 1888, and Serial No. 285,625, filed September 17, 1888.

Having thus described my invention, the following is what I claim as new therein and 40 desire to secure by Letters Patent:

1. A crucible-bowl provided with a movable partition extending to the bottom of said crucible, for the purpose set forth, and flanges adapted to overlap the edges of said partition, substantially as and for the purposes set forth.

2. The combination, with the crucible-bowl, of flanges within said bowl, a partition adapted to rest against said flanges, and lugs for 50 locking said partition to the flanges, substantially as set forth.

3. The combination, with the crucible-bowl having tapering sides, of flanges fitted within said crucible and extending upward from the 55 bottom thereof and a removable partition resting on the bottom of the crucible and overlapping and resting against said flanges, substantially as set forth.

NEWTON R. WILSON.
